UNITED STATES PATENT OFFICE.

SAMUEL SEGAL, OF NEW YORK, N. Y., ASSIGNOR TO SEGAL AUTOMATIC TWEEZER CORPORATION, OF NEW YORK, N. Y., A CORPORATION OF NEW YORK.

LIGHTER.

Application filed January 7, 1928. Serial No. 245,061.

This invention relates to a functionally and structurally improved lighter of that type which is particularly intended to be employed as a smoker's accessory or appliance.

5 Specifically, it is an object of the invention to construct a device of this character which may be employed freely without danger of soiling the hands of the user.

A further object of the invention is that 10 of furnishing a lighter, the parts of which may be readily disassembled by the user when necessary and in which the danger of accident occurring is reduced to a minimum.

A still further object is that of constructing 15 a device of this type in which the parts will have a somewhat automatic operation, the operator being required to deliberately manipulate the parts to only a minimum extent.

20 Another object is predicated upon the furnishing of a lighter which will preferably embody a construction rendering it extremely desirable for use as a table or desk appliance.

An additional object is that of furnishing 25 a device of this type, the parts of which will be relatively few in number and individually rugged in construction, these parts being assembled readily by labor which may be comparatively unskilled and which, when so assembled, will operate over long periods of 30 time with freedom from difficulty, the article being capable of being manufactured at a relatively nominal figure.

With these and further objects in mind 35 reference is had to the attached sheets of drawings, in which there is illustrated various practical embodiments of the invention and in which:

40 Figure 1 is a side elevation of one form of lighter;

Fig. 2 is a sectional plan view taken along the line 2—2 in the direction of the arrows of Fig. 1;

45 Figs. 3, 4, 5, 6 and 7 are views similar to Fig. 1, but showing different forms of construction and certain of the parts being broken away to disclose underlying structure;

Fig. 8 is a plan view of the deck or top portion of a lighter;

50 Fig. 9 is a fragmentary sectional side view thereof, and

Fig. 10 is a transverse view taken along the lines 10—10 and in the direction of the arrows of Fig. 9.

In these views the numeral 15 indicates 55 the casing of the lighter, which is preferably formed, at its lower end, with a base portion 16, so that it may be supported in a stable manner upon any desirable surface. At its upper end this casing provides a deck from 60 which there extends—in the embodiment illustrated—a spout or nozzle 17 beyond which projects a wick 18. Also supported upon the deck—preferably in a manner hereinafter brought out—is a sparking disk 19 which engages with a sparking element such as flint 20 in order, when these elements are moved 65 relatively and in a proper manner, to direct a spray of sparks towards the exposed wick portion. It will, of course, be understood 70 that the casing 15 accommodates the inner end of the wick and that this casing is filled with a suitable volatile fluid or other substance with which the wick may act by capillary attraction in such manner that a flame 75 will be produced. The flame at the exposed end of the wick is extinguished by the use of a snuffer cap 21 mounted to cooperate with the nozzle or spout to form a seal at this point. 80

Now referring to the embodiment of the invention illustrated in Figures 1 and 2 it will be seen that the snuffer or cap 21 is mounted upon or forms a part of an arm 22 and that the casing 15 is encircled by a sleeve 23 slidably enveloping the body thereof. As has been shown particularly in Figure 2, the casing preferably has its walls bulged inwardly, as at 24, to form a receptacle portion which is isolated from the case interior. The 85 sleeve in this form carries a rivet or pin 25 which extends through a slot 26 provided in line with the receptacle portion 24 and a rod 27 is attached at its lower end to this connecting element and mounts, at its upper end, 90 a link 28 which is in turn secured to the arm 22. 95

As a consequence it will be appreciated that, normally, the snuffer will be in the position shown in Figure 1, but if a person 100 grasps the device he will necessarily grip the sleeve 23 in lifting the same from the

surface supporting the lighter and thus, by means of the rod and link, the arm will be swung upwardly to the position indicated in dotted lines, at which the wick end is exposed to a spray of sparks emanating from the point of contact of the sparking disk and flint.

In the form of lighter shown in Figure 3 no slidable sleeve encircles the casing 15, but this casing is formed with a tube portion 29 extending longitudinally of its body and out of communication with the interior of the casing. The arm 22 is extended, as at 30, and is link-connected as at 31, to a rod 32 extending within the tube. This rod may normally be urged downwardly either by having a weight 33 attached to its lower end or by a spring 34 which is provided to achieve this function. Also, obviously as shown, both of these factors may be employed and, in any event, the end of the rod or a continuation thereof is of sufficient length that, with the snuffer cap in wick-enclosing position, this end portion rests in the same plane as the lower edge of the casing or the base portion thereof.

Thus, it is obvious that with the lighter in a position of rest upon a supporting surface, the upper end of the wick is enclosed to prevent the escape of the fuel within the casing. Also, if elevated from such supporting surface the snuffer cap automatically swings to the position shown in the figure in question, it being patent that after the device has been used and is returned to its supporting surface, the snuffer cap assumes a position at which it extinguishes the flame.

In the form of lighter shown in Figure 4 a slidable sleeve is employed encircling the casing and the arm 22 has, at its inner end and point of pivotal mounting, an arcuate rack portion 35, which is actuated by a rack 36 secured to the sleeve 23, a pinion 37 being mounted for rotation upon the upper face of the deck and being interposed between the racks 35-36. Accordingly, as the lighter is lifted from a supporting surface the wick will be uncovered and upon the return of the lighter the parts will assume their normal position, in which the flame will be snuffed automatically. Likewise, the lighter illustrated in Figure 6 embraces the aforedescribed casing encircled by the slidably mounted sleeve, the casing being formed with a slot 38 and opening 39, through which there extends a strip 40 which is attached to the sleeve and which may have a certain inherent and limited resiliency. The arm 22 is, in this instance, formed with a projecting portion 41 in its lower edge, which portion is overlapped by the upper end of the spring strip. Obviously, as afore-described, a lifting of the lighter will result in an uncovering of the wick and a replacing of the lighter upon a supporting surface will automatically extinguish the flame.

Similarly, in Figure 7, a slidable sleeve is provided and, in this instance, in lieu of mounting the snuffer supporting arm upon the upper deck, an arm 42 is furnished by extending a portion of the sleeve and this arm mounts, at its upper end, a snuffer cap 43, it being here noted that such mounting is preferably pivotal. Obviously, the same function as has been described in connection with the previously referred to figures, will occur and the purpose of having the cap pivotally mounted will be apparent for the reason that, as the lighter body is tilted in use the cap will tend to swing to a point relatively remote from the flame, it being appreciated that the point of pivotal mounting is well above the center of gravity of the snuffer cap.

With reference to the final form of lighter shown, i. e. that in Figure 5, the cap arm 22 is extended, as at 44, and formed with a slot 45 in such extension, within which slot a pin 46 slidably moves. This pin is carried by the upper end of a lever 47, the lower end of which is pivotally mounted as at 48. Obviously, as the lighter is grasped in order to elevate the same, the lever will be swung inwardly, thus uncovering the upper wick end. If it is found that the weight and camming action exerted by the arm 22 and cap are inadequate to return the lever to its normal position, to wit: that shown, the lever may be urged to such position by interposing between its body and the face of the case a spring 49, which will obviously accomplish the result desired.

Now, with a view to providing a spark-producing structure, it is preferred that a construction similar to that shown in Figures 8, 9 and 10 be employed. In these views it will be observed that the sparking disk is mounted upon a shaft 50 which may have an irregular contour, so that, while the disk is slidable with respect thereto these elements will turn in unison. This shaft has bearing in the forked end portion 51 of a tube 52, and the shaft mounts, as a fixed part, a thumb-wheel 53. At this time it will be noted that the size of the sparking disk is such that there will be no danger of the thumb of the operator coming in contact therewith, when actuating the thumb-wheel 53. In other words, the latter is made relatively so much larger than the disk that this cannot occur. Also, if desired, the forked portion 51 may be of such area as to cover, adequately, the disk.

The tube is secured to a block 54, the latter covering a filling opening 55 in the deck of the casing and, in order normally to maintain the proper position of the parts, the shaft 50 may have a reduced end portion 50' extending within an opening or recess in the casing deck. However, obviously, due to the fact that this shaft is capable of axial movement with respect to the disk, it may, by exerting pressure upwardly against the thumb wheel, be moved to a point at which its reduced end portion 130

clears the deck of the casing, it being then obvious that the tube, together with its shaft assembly and block, may thereupon be withdrawn from position upon the case. At this

5 time it will be observed that a lug 56 is provided upon the case deck and is formed with a bore for the accommodation of the rear end of the tube and may be formed with a further bore for the reception of flints 57, 10 this latter bore being normally closed by the inner face of the block 54 and the latter having a lower surface corresponding to the upper surface of the case so as to provide proper bearing at this point.

15 In order to assure against an accidental displacement of the shaft and, further, with a view to returning the same to normal position, the upper end of the snuffer cap may have an extension 58 which overlies the upper 20 end of the shaft 50 and if the latter projects beyond the forked portion 51 it will be apparent that it will be forced downwardly to the position shown in Figure 9 upon the cap assuming its seated position. Obviously, if 25 desired, in conjunction with this structure a spring-pressed pin 59 may be employed co-operating with the arm 22 of the snuffer cap and the spring for this pin may be housed within a compartment having side walls, as 30 at 60.

With the foregoing it will be understood that, among others, the objects specifically aforementioned are achieved. It is intended, however, that numerous changes in construction and rearrangement of the parts might be resorted to without departing from the spirit 35 of the invention as defined by the claims.

Having described my invention, what I claim as new and desire to secure by Letters 40 Patent is:

1. A lighter including a body, flame extinguishing and producing mechanisms associated with said body and means slidably associated with said body and connected to 45 said flame extinguishing mechanism for operating the same upon said means being released from the grasp of a person when the lighter is rested upon a supporting surface.

2. A lighter including a body, flame extinguishing and producing mechanisms associated with said body and means slidably within said body and connected with said flame extinguishing mechanism to render the same operative responsive to the lighter being 55 rested upon a supporting surface.

3. A lighter including a fuel receiving body formed with an opening, spark producing mechanism adapted to be mounted upon and shiftable with respect to said body, said mechanism in mounted position having a portion thereof covering the opening, into said body.

4. A lighter including a mounting lug, a block movable with respect thereto, a wick extending adjacent said block, a spark producing mechanism carried by said block, said

lug being formed with an opening affording storage for sparking elements and said block normally covering said opening.

5. A lighter including a body, a wick extending from said body, a lug also extending from said body and formed with a bore, a block slidably mounted upon said body and adjacent said lug, a sparking mechanism secured to said block and extending within the bore of said lug, a shaft forming a part of said sparking mechanism, said shaft being adapted to retain said block against movement with respect to said lug.

6. A lighter including a body, a spark producing mechanism mounted upon said body, a wick adjacent said spark producing mechanism, a shaft forming a part of the latter, and means movable with respect to said spark producing mechanism to engage said wick and assure the setting of said shaft in a pre-determined position.

7. A lighter including a casing formed with a wick opening, a flame snuffing member co-operating with said opening, means for movably mounting said member with respect to 90 said casing and means connected with said mounting means to automatically move said snuffing member to inoperative position upon the latter being lifted from a supporting surface.

8. A lighter including a casing formed with a wick opening, a snuffing cap cooperating with said wick opening, a lever mounting said cap and a rod movably mounted by said casing and connected with said lever to shift 100 the cap automatically to inoperative position upon said lighter being lifted from a supporting surface.

9. A lighter including a casing, a rod slidably mounted by said casing, means whereby 105 said rod normally tends to extend below said casing, a wick extending from the casing, a snuffer cap cooperating with the wick and means connecting the cap with said lever whereby the cap will move to inoperative 110 position upon the lighter being lifted from a supporting surface.

10. A lighter including a casing, a tube associated with said casing, a rod slidably mounted within said tube and extending below the same, a wick extending from the casing, a snuffing cap cooperating with said wick and means connecting said cap with said rod whereby the former will be shifted to inoperative 115 position upon the lighter being lifted from a supporting surface.

11. A lighter including a casing formed with an opening, a wick extending through said opening, a snuffer cooperating with said wick and mounted by said casing, a tube 125 formed with a forked end portion disposed adjacent said wick, means for slidably securing said tube to said casing, a plug of pyrophoric material within said tube, a 130 a sparking disk disposed within the arms of

- 5 said forked portion and being of such size as to be substantially enclosed thereby, an axially shiftable shaft extending between and below such arms and mounting said disk, said 40
5 shaft extending in contact with said casing to prevent a shifting of said tube, and a thumb wheel of a diameter materially larger than the arms of said forked portion and secured to said shaft at a point between the 45
10 lower arm of the fork and the upper face of the casing, said thumb wheel and shaft being shiftable to permit a removal of said tube.
12. A lighter including a casing formed with an opening, a wick extending through 50
15 said opening, a sparking mechanism disposed adjacent said wick and mounted by said casing, a lever rockingly mounted by said casing, a rod slidably disposed with respect to said casing and to be shifted by engagement with 55
20 a surface supporting said casing, a link connecting said rod with said lever to shift the same as the lighter is removed from said supporting surface, and a snuffer cap adjacent the end of said lever to normally cover the 60
25 wick.
13. A lighter including a casing formed with a fuel opening in its upper surface, a spark-producing mechanism mounted upon said casing, a member also mounted upon 65
30 said casing and normally covering said opening, and means for normally retaining said member in opening covering position.
14. A lighter including a casing, a spark-producing mechanism movably mounted 65
35 upon said casing, a shaft for actuating said mechanism and having bearing in said cas-
- ing to normally prevent a removal of said mechanism from said casing, means whereby said shaft may be shifted and a wick extending from said casing adjacent said spark-producing mechanism. 40
15. A lighter including a casing, a spark-producing mechanism movably mounted upon said casing, a shaft for actuating said mechanism and having bearing in said casing to normally prevent a removal of said mechanism from said casing, a thumb wheel affixed to said shaft and whereby said mechanism may be operated and said shaft may be shifted to permit a removal of said mechanism from said casing and a wick extending from said casing adjacent said spark-producing mechanism. 45
16. A lighter including a casing, a spark-producing mechanism movably mounted upon said casing, a shaft for actuating said mechanism and having bearing in said casing to normally prevent a removal of said mechanism from said casing, a thumb wheel affixed to said shaft and whereby said mechanism may be operated and said shaft may be shifted to permit a removal of said mechanism from said casing, a wick extending from said casing adjacent said spark-producing mechanism, a snuffer cap cooperating with 55
60 said wick and means associated with said cap and engaging said shaft to normally maintain the same in bearing relationship with respect to said casing. 65

In testimony whereof I affix my signature.

SAMUEL SEGAL.
